CLAIM

The ornamental design for a panel for biochemical analysis as shown and described.

DESCRIPTION

FIG. 1 is a perspective view from front side of a panel for biochemical analysis showing our new design;

FIG. 2 is a partial enlarged view of FIG. 1;

FIG. 3 is a perspective view from rear side thereof;

FIG. 4 is a partial enlarged view of FIG. 3;

FIG. 5 is a front elevational view thereof;

FIG. 6 is a rear elevational view thereof;

FIG. 7 is a left side view thereof;

FIG. 8 is a top plan view thereof;

FIG. 9 is a sectional end view of A-A' in FIG. 5 without internal mechanism thereof;

FIG. 10 is a sectional end view of B-B' in FIG. 5 without internal mechanism thereof;

FIG. 11 is an enlarged sectional end view of C-C' in FIG. 5 thereof;

FIG. 12 is a perspective view from front side showing the article in an alternate configuration; and,

FIG. 13 is another perspective view from front side showing the article in an alternate configuration.

The even broken lines in the figures show portions of the panel for biochemical analysis that form no part of the claimed design, and the uneven broken lines in the figures show boundaries of the claimed design.

The cap of the panel represented by broken lines in FIG. 12 and FIG. 13 is for purposes of illustrating environment only, and which form no part of the claimed design. The panel is formed of transparent material, but the portions of the design which are visible through the transparent walls have been omitted for convenience of illustration.
